UNITED STATES PATENT OFFICE

117,093

DESIGN FOR A COMBINED KEY AND KNIFE

Irving Florman, New York, N. Y.

Application August 14, 1939, Serial No. 86,673

Term of patent 7 years

To all whom it may concern:

Be it known that I, Irving Florman, a citizen of the United States, residing at New York, in the county of New York and State of New York, have invented a new, original, and ornamental Design for a Combined Key and Knife, of which the following is a specification, reference being made to the accompanying drawing, forming a part thereof.

Fig. 1 shows a front view of my combined key and knife with the blades closed;

Fig. 2 is a similar view with the blades open;
Fig. 3 is a back view of the combined key and knife with the blades open, and
Fig. 4 is a side view thereof.

I claim:

The ornamental design for a combined key and knife, substantially as shown.

IRVING FLORMAN.
